UNITED STATES PATENT OFFICE

149,718

DESIGN FOR A BROOCH

Andrew Zborovszky, Hamilton, Ontario, Canada,
assignor to Brown & Mills, Inc., Providence,
R. I., a corporation of Rhode Island

Application August 7, 1946, Serial No. 132,345

Term of patent 3½ years

(Cl. D45—19)

To all whom it may concern:

Be it known that I, Andrew Zborovszky, a subject of Great Britain and residing at Hamilton, in the Province of Ontario and Dominion of Canada, have invented a new, original, and ornamental Design for a Brooch, of which the following is a specification, reference being had to the accompanying drawing, forming part thereof.

Fig. 1 is a plan view of a brooch, showing my new design; and

Fig. 2 is a side view of the same.

I claim:

The ornamental design for a brooch, as shown.

ANDREW ZBOROVSZKY.
